UNITED STATES PATENT OFFICE.

JOHN LUKASZEWSKI, OF CHICAGO, ILLINOIS.

SWITCH.

Application filed April 30, 1925. Serial No. 27,005.

To all whom it may concern:

Be it known that I, JOHN LUKASZEWSKI, a citizen of the United States of America, residing at Chicago, in the county of Cook 5 and State of Illinois, have invented certain new and useful Improvements in Switches, of which the following is a specification.

The present invention relates to improvements in switches.

10 The primary object of this invention is the provision of a switch adapted for use in radio and many other types of circuits and is characterized by the removability of a certain portion or portions of the switch 15 from the main portion, whereby several, relatively movable, electric instrumentalities may be distantly separated, or one or several movable electric instrumentalities and their source of current supply may be 20 distantly separated without necessitating the disconnection of the lead wires, extending from said instrumentalities or current supply, from the elements of the switch to which they are connected when the switch 25 is assembled for operation.

Other objects and advantages of the invention will be apparent during the course of the following description.

In the accompanying drawings forming a 30 part of this specification and in which like numerals are employed to designate like parts throughout the same,

Figure 1 is a plan view of a type of switch embodying this invention,

35 Figure 2 is an end elevational view of the switch structure shown in Fig. 1,

Figure 3 is a transverse sectional view taken upon line III—III of Fig. 1,

40 Figure 4 is a fragmentary top plan view of the switch structure shown in Fig. 1 and illustrates the manner in which a portion of the switch may be separated from the main body portion,

45 Figure 5 is a top plan view of a modified form of switch embodying this invention,

Figure 6 is an end elevational view of the form of switch shown in Fig. 5,

50 Figure 7 is a fragmentary perspective view of the main body portion of the switch structure shown in Fig. 1,

55 Figure 8 is a fragmentary perspective view of one end of a removable portion of a switch capable of being used in connection with either of the types of switches shown in Figs. 1 and 5, and

Figure 9 is a fragmentary perspective

view of one end of the body portion of the switch structure shown in Figs. 5 and 6.

In the drawings, wherein for the purpose of illustration is shown a preferred embodiment of this invention, the numeral 5 in Figs. 1 to 4 inclusive and 7 designates the main body portion or mounting block of a switch which is shown in Figs. 1 and 7 as having the laterally projecting arms 6 which are cutaway inwardly from their top faces to form the grooves 7 and shoulders 8 extending right angularly to the said grooves. This main body portion or mounting block 5 is illustrated as having fastened thereto 70 the pivotally movable members or blades 9 which are connected at their free ends by the strip 10 having the operating knob 11. In Fig. 3 the fastening elements 12 for the movable members 9 are illustrated as having 75 terminals 13 extending therefrom to which electric lead wires, not shown, may be connected by the screws 14.

A strip 15 is shown in Figs. 1, 3, 4, 7 and 8 as having the tongues 16 extending longitudinally from the opposite ends thereof and shaped to be received within the grooves 7 formed in the arms 6. The end portions of the strip 15, adjacent the tongues 16, are adapted to rest upon the shoulders 8 when 80 the tongues are positioned in the grooves 7. The end faces 15^a, see Figs. 4 and 7, of the strip 15 are intended to engage the faces 6^a of the arms, formed by the cutting away 85 of the arms to provide the shoulders 8, to 90 prevent longitudinal shifting of the strip 15 in respect to the mounting block 5. To removably hold the strip 15 in the position illustrated in Figs. 1, 3 and 4, with the tongues 16 received within the grooves 7, 95 the latch members 17 are pivoted at 18 to the main body portion or mounting block 5 and are adapted to be arranged to overlie the tongues 16. To permit the removal of the strip 15, the latch members 17 may be swung 100 into the position illustrated in Fig. 7 for permitting the tongues 16 to be lifted out of the grooves 7. The strip 15 is provided with the contacts 19 which are provided in equal numbers to the movable members or 105 blades 9 and are arranged in alinement therewith. The contact members 19 are illustrated in Figs. 1, 3 and 4 as being provided with the terminals 20 to which electric lead wires, not shown, may be fastened 110 by the screws 21.

It will now be seen that the strip 15 may

be very quickly and easily assembled or disassembled in respect to the main body portion or mounting block 5 of the switch and when assembled will be properly located to align 5 the contacts 19 with the movable members or blades 9 so that pivotal movement of these members toward the contacts 19 will cause the said members and contacts to electrically engage each other. Fastening means receiving 10 apertures may be formed at any desired points in the main body portion or mounting block 5 or they may be formed in the grooved portions of the arms 6 where the heads of the fastening means will be concealed 15 when the entire switch is operatively assembled. To permit the latch members 17 to be easily and conveniently shifted into their locking or unlocking positions, the operating knobs 22 are suitably connected 20 to the free ends thereof.

In Figs. 5, 6 and 9 a modified form of switch structure is illustrated. This switch structure includes the main body portion or mounting block 23 having the arms 24 projecting laterally therefrom and arranged in opposed pairs. Each of these arms 24 is cutaway to form a groove 25 and a shoulder 26. The same type of removable strip 15 may be used in connection with this main body portion or mounting block 23 and its laterally projecting arms 24. In this switch structure, however, two strips 15 are employed instead of the single strip shown in Figs. 1 to 4 inclusive. These strips are provided with contact members 19 which will be arranged in longitudinal alinement with the movable members or blades 9 carried by the fastening means 12 by means of which the said members or blades 9 are secured to 30 the main body portion or mounting block 23. The pair of removable strips 15 are each provided with a pair of pivotally mounted latch members 17^a. The latch members 17^a at each end of the main body portion or mounting block 23 are connected to the latter by the common fulcrum pins 18^a, as best 35 illustrated in Figs. 5 and 6.

The movable members or blades 9 are connected to move in unison by the member 10^a 40 which is provided with an operating knob 11^a, as best illustrated in Figs. 5 and 6.

It will now be seen that with the strips 15 operatively assembled in respect to the mounting block 23, the movable members or blades 9 may be swung in either direction for 45 selectively bringing the same into engagement with the contacts carried by either strip 15. This movement of the members 9 is clearly illustrated in full lines and dotted lines in Fig. 6.

It is now believed that the method of constructing and manner of operating the different forms of switches embodying this invention will be clearly understood from the 50 above detail description and the accompany-

ing drawings, however, it might be well to note that these types of switch structure are especially adapted for use in connection with radio sets or other types of movable electric instrumentalities. It will be noted, in connection with a radio set, that either of the types of switches may be mounted upon or within a radio cabinet whereby the control or tuning instrumentalities within the cabinet may be connected to the movable members or blades of the switches and such elements as an antenna, a loud speaker unit, an A battery, and a B battery may be connected to the contacts carried by the removable strips 15. With this arrangement, the 55 said strips could be separated from the main body portion or mounting block of the switch when the radio cabinet was to be removed to a distant point. The removable strips, thereby, permitting the various lead wires to remain connected to the contacts and the movable members or blades. This general type of switch is equally adapted for use in connection with portable machines driven by self-contained electric motors. 60 When used in connection with such instrumentalities, the main body portion or mounting block of the switch may be mounted permanently upon the movable machine or its electric power unit. The machine may then be moved to any of its predetermined points of operation, or points where electric current supply lines are available, and by having the electric current supply lines connected to the contact members of a removable 65 strip, the strip at that particular location may be quickly mounted in place and the movable members or blades pivoted to close the circuit desired.

It is to be understood that the forms of 70 this invention herewith shown and described are to be taken as preferred examples of the same, and that various changes in the shape, size, and arrangement of parts may be resorted to without departing from the spirit 75 of the invention or the scope of the subjoined claims.

Having thus described the invention, I claim:

1. In a switch, a mounting block, a plurality of grooved arms projecting therefrom, a plurality of movable members fastened to the block, a plurality of contacts, a support for said contacts and receivable in said grooves, and latch members movable into and out of positions covering the grooves for removably holding said support in said grooves in a position to permit said members to be moved into engagement with said contacts.

2. In a switch, a mounting block, a plurality of grooved arms projecting therefrom, a plurality of movable members fastened to the block, means connecting said members to cause them to move in unison, a multiplicity

of contacts divided into two sets, a support for each set and receivable in said grooves, and latch members for removably holding said supports in the grooves in positions to 5 permit the members to be selectively moved into engagement with either set of contacts.

3. In a switch, a mounting block, a plurality of arms projecting therefrom, said arms each having a groove formed therein, a plurality of movable members fastened to said 10 block, a plurality of contacts to be engaged by said movable members, a support for said contacts having tongues to be received in said grooves, and means for removably 15 holding said tongues in said grooves.

4. In a switch, a mounting block, a pair of arms projecting laterally from opposite sides of said block, said arms each having a groove formed therein, a plurality of interconnected movable members fastened to said block, a 20 multiplicity of contacts divided into two sets, a support for each set having a pair of tongues to be received in the grooves of one pair of arms, and means for independently removably holding said tongues in said 25 grooves, said members being adapted to be moved into engagement with either set of contacts.

In testimony whereof I affix my signature.
JOHN LUKASZEWSKI.
